UNITED STATES PATENT OFFICE.

CHARLES W. NEUSBAUM, OF ROCHESTER, NEW YORK, ASSIGNOR TO BEECHNUT PACKING COMPANY, OF CANAJOHARIE, NEW YORK, A CORPORATION OF NEW YORK.

WRAPPING AND SEALING MACHINE.

Application filed March 27, 1922. Serial No. 547,157.

To all whom it may concern:

Be it known that I, CHARLES W. NEUSBAUM, of Rochester, in the county of Monroe and State of New York, have invented 5 certain new and useful Improvements in Wrapping and Sealing Machines; and I do hereby declare the following to be a full, clear, and exact description of the same, reference being had to the accompanying 10 drawings, forming a part of this specification, and to the reference numerals marked thereon.

My present invention relates to packaging machines, and more particularly to machines 15 for wrapping and sealing packages. These are often covered with a wrapping of paper or foil or both coated or impregnated with paraffin and to complete the wrapping and sealing the flaps of the wrapper must be 20 folded down and heated to fuse the paraffin. My invention has for its object the provision of a very simple, but effective machine that will rapidly perform these operations 25 and deliver the package tightly sealed. The improvements are directed in part toward the provision of means that will insure the adherence of the under flap at an end of the package to the body of the latter and the adherence of the outer flap to the inner 30 flap. To these and other ends the invention consists in certain improvements and combinations of parts, all as will be hereinafter more fully described, the novel features 35 being pointed out in the claims at the end of the specification.

In the drawings:

Figure 1 is a top plan view of a wrapping and sealing machine constructed in accordance with and illustrating one embodiment 40 of my invention;

Figure 2 is a side view thereof;

Figure 3 is an enlarged fragmentary side view of the front end of the table;

Figure 4 is a vertical central section 45 through the same portion of the table;

Figure 5 is a detail section on the line 5-5 of Figure 3;

Figure 6 is a detail section on the line 6-6 of Figure 4;

Figure 7 is a detail section on the line 7-7 of Figure 3;

Figure 8 is a detail section on the line 8-8 of Figure 3;

Figure 9 is a perspective view of the package as it is presented to the machine;

Figure 10 is a similar view of the package after the under flap has been folded;

Figure 11 is a perspective view of the package completely folded and sealed, and

Figure 12 is a collective enlarged detail 60 perspective view of the sealing plate supporting bracket.

Similar reference numerals throughout the several views indicate the same parts.

The present invention contemplates the provision of a machine for only partially wrapping but completely sealing a package to which the wrapper has been preliminarily applied by hand in the manner shown in Figure 9 where A represents the body of 70 the package with four sides completely covered and the ends only partially covered by the folding in of the two short flaps B leaving the longer upper and lower flaps C and D still extended in which shape an operator can conveniently and quickly prepare the package which is then placed on the machine and completed. In the present embodiment of the invention I provide a 75 table top 1 constituting a bed preferably surfaced with metal at 2 and of the form shown in the cross sectional view with a channel 3 down the center thereof. At the ends of the table are brackets 4 providing bearings for sprockets 5 which support an 80 endless chain 6 having conveyor fingers 7 thereon at suitably spaced intervals. The chain travels in the direction of the arrow and the upper reach thereof occupies the 85 channel 3 in the bed. 90

At the front end of the machine (which is at the right in the figures) is a rectangular package receiving pocket 8 through which the conveyor travels, which pocket is open on its rear side to allow the package 95 to slide out on the conveyor while a low wall or bead 9 defines the other sides. The pocket is preferably formed in two parts consisting of plates 10 adjustably mounted by screws 11 on the bed to accommodate 100 packages of different length, and it is rectangular in form, the present machine being adapted for sealing a rectangular package.

Next beyond the pocket are a plurality 105 of vertically disposed plates successively arranged in lines on each side of the conveyor and constituting a runway which the latter traverses. These plates have rigidly attached to them brackets 12 that have a sliding bearing on the top of the table or bed 110

and are provided with laterally projecting guide pins 13 surrounded by springs 14. The guide pins take into guiding apertures 15 in slotted brackets 16 adjustably secured 5 to the bed by screws 17, the springs 14 acting between the bracket to urge the bracket 12 and its plate inwardly in each instance. The guide pins are capped by thin screws or wing nuts 18 bearing against the outer 10 sides of the brackets 16 to limit this inward movement adjustably and define the width of the runway through which the package is to pass. Preferably the brackets 16 are undercut as shown at 19 in Figure 12 and 15 the brackets 12 are forked in a complementary manner as shown at 20 to cooperate therewith and be further guided and steadied. The first two sets of brackets at the front or right end of the machine are 20 not so formed in the present instance inasmuch as their guide pins must be offset and are carried by upstanding outer extensions or flanges 12.

Assuming the progression to be from the 25 pocket 8 down the runway along the course of the conveyor chain 6, the first plate is a heated folding and sealing plate 21 having an upwardly inclined and laterally turned advance lip 22, it being understood that in 30 the following description the elements referred to are duplicated on the two sides of the runway. This plate 21 is heated by a suitable electrical hot point 23, the terminals of which are indicated at 24 and 35 the lead wires at 25. The next plate 26 is also a heated plate presenting a plane vertical surface on the interior of the runway. It too is provided with a hot point 23 and with terminals 24 having lead wires 40 25a. An otherwise unsupported and laterally yielding extension of this plate 26 extends forwardly at 27 above the plate 23 and is provided with a downwardly inclined and laterally flared lip 28 at the rear extremity 45 of which is a small flared lip 29 that is very steeply inclined rearwardly and best shown in Figure 3. Beyond the plate 26 and constituting the far end of the runway is a similar vertical plate 30 which is however unheated. 50

To hold the moving packages down against the bottom of the runway I provide therein a pair of long overhanging and longitudinally extending shoe 31 in the 55 present form of rods having upturned forward ends 32. These are resiliently supported to yield upwardly but press sufficiently upon the packages to which end they are provided with fixed vertical posts 33 surrounded by coil springs 34 and extending through and guided by bridge pieces 35 on the top side of which they are capped by nuts 36, the bridge pieces being of the form shown in Figure 6 and secured to the table 60 as indicated at 37 in Figure 1.

The machine operates as follows:

Packages A in the condition illustrated in Figure 9 are successively placed by the operator in the pocket 8 which they fit rather closely. The rounded bead 9 of the pocket 70 as a result of this causes the lower flap D to fold upwardly as shown in Figure 3 either flat against the end of the package or approximately so. A finger 7 on the conveyor then picks up the package as in 75 Figure 4 and carries it between the hot plates 21, the inclined lips 22 of which complete the folding of the flap D if this has not already been done. The flat heated surface of these plates then press the flap D flat against the end face of the package and seal it there by fusing or melting the wax with which the parts are impregnated or coated as shown in Figure 10. In the meantime the upper flap C has in each instance been guided up the incline 22 and entered between the plates 21 and 27. The lip 28 on the latter as the package progresses 80 folds the upper flap C downwardly upon the lower flap which movement is completed by the lip 29 and the two superposed flaps then pass on to the hot plate 26 in the condition shown in Figure 11, and this hot plate which is high enough to engage both flaps and cover the entire end of the package completes the melting of the paraffin and seals the upper flap upon the lower. The package then quickly passes on to the cold plates 30 which cool and set the paraffin and complete the treatment, it being understood that 85 all of these yielding plates contribute the function of flattening and ironing out the end of the package so that it is square and smooth. The conveyor finally carries the package from between the cold plates 30 into a suitable chute 38 from which it is delivered as desired. 90

It is obvious from the construction shown that the machine can be adjusted and fitted to packages of different sizes within a certain range. 100

The function of my improved machine wherein it flattens, heats and seals the lower flap and then flattens, heats and seals the upper flap and both flaps together is important in that in operating upon heavy wrappers and particularly where heavy foil is used the thermal changes are such that attempting to seal both flaps at once lacks uniformity in results. 110

I claim as my invention:

1. In a wrapping and sealing machine, the combination with a table, a runway thereon and a conveyor traversing the runway at a uniform rate, of a fixed package 115 receiving pocket at one end of the runway receiving pocket at one end of the runway adapted to fold upwardly the lower end flap of a partially wrapped package when placed therein, means at the side of the runway for folding down the other flap as the 120

package travels on the conveyor and means for heating the folded flaps to seal them upon the package.

2. In a wrapping and sealing machine, 5 the combination with a table, a runway thereon and a conveyor traversing the runway at a uniform rate, of a fixed package receiving pocket at one end of the runway adapted to fold upwardly the lower end flap 10 of a partially wrapped package when placed therein, means at the side of the runway for pressing said flap inwardly relatively elevated means for subsequently folding the upper flap down upon the lower flap and 15 means for successively heating the folded flaps.

3. In a wrapping machine, the combination 20 with a table, a runway thereon and a conveyor traversing the runway at a uniform rate, of heated means at the side of the runway for engaging the outer face of the lower flap of a partially wrapped package to simultaneously heat and press the flap against the body of the package, and 25 relatively elevated and overlying means at the side of the runway for later heating and folding the upper flap down upon the lower flap.

4. In a wrapping machine, the combination 30 with a table, a runway thereon, and a conveyor traversing the runway at a uniform rate, of heated means at the side of the runway for engaging the outer face of the lower flap of a partially wrapped package, 35 to heat and press said flap against the body of the package, similarly arranged heated means for later folding the upper flap down upon the lower flap and heated means further down the runway for pressing and sealing both flaps.

5. In a wrapping machine, the combination 40 with a table, a runway thereon, and a conveyor traversing the runway, of a laterally flared and upwardly inclined heated plate at the side of the runway for engaging the outer face of the lower flap of a partially wrapped package to heat and press said flap against the package, and a laterally flared and downwardly inclined heated plate 45 for later folding the upper flap thereof down upon the lower flap to heat and seal it thereon.

6. In a wrapping machine, the combination 55 with a table, a runway thereon, and a conveyor traversing the runway, of a laterally flared and upwardly inclined heated plate at the side of the runway for engaging the outer face of the lower flap of a partially wrapped package to heat and press said flap against the package, a laterally flared and downwardly inclined heated plate 60 for subsequently folding the upper flap thereof down upon the lower flap, and heated means further down the runway for thereafter sealing both flaps. 65

7. In a wrapping and sealing machine, the combination with a table, a runway and a conveyor traversing the latter, of a plate 70 adapted to cooperate with a package on the conveyor and having a laterally extending guide pin thereon, a bracket on the table through which the guide pin extends, a spring acting between the said bracket and plate and a bracket on the plate slidable on the table and guided on said first mentioned bracket. 75

8. In a wrapping and sealing machine, the combination with a table having a runway and a continuous conveyor traversing the runway, of heated means at the side of the runway for pressing and heating the flap of a partially wrapped package carried by the conveyor against the body of the package and additional means upon the table for subsequently engaging the outer 80 face of another flap to fold, heat and press it upon the first mentioned flap. 85

9. In a wrapping and sealing machine, the combination with a table having a runway and a continuous conveyor traversing the 90 runway and having upstanding members for advancing a partially wrapped package thereon, folding and heating means adjacent the conveyor for heating and folding one set of flaps on the packages against the 95 bodies thereof, and additional heating and folding means adapted to subsequently heat and fold opposite sets of flaps upon the packages against the bodies thereof, each of said folding and heating operations being 100 performed during the continuous advancement of the packages.

CHARLES W. NEUSBAUM.
